UNITED STATES PATENT OFFICE

164,748

CHILD'S PLAY BOOTH

James Moir Webster, Pelham, N. Y.

Application April 18, 1950, Serial No. 9,297

Term of patent 7 years

(Cl. D33—7)

To all whom it may concern:

Be it known that I, James Moir Webster, a citizen of the United States of America, residing at Pelham, in the county of Westchester, in the State of New York, have invented a new, original, and ornamental Design for a Child's Play Booth, of which the following is a specification, reference being had to the accompanying drawing, forming a part thereof, in which:

Fig. 1 is a plan view of a child's play booth embodying my new design;

Fig. 2 is a side elevation of the play booth shown in Fig. 1;

Fig. 3 is a front and side perspective view of the play booth shown in Fig. 1; and

Fig. 4 is a rear and side perspective view of the play booth.

The characteristic features of my design are shown in full lines.

I claim:

The ornamental design for a child's play booth, substantially as shown and described.

JAMES MOIR WEBSTER.
